ENGINE VALVE

Filed March 29, 1927

UNITED STATES PATENT OFFICE

JOHN H. GRUBE, OF PASADENA, CALIFORNIA, ASSIGNOR TO GRUBE SILENT MOTORS INCORPORATED, OF PHOENIX, ARIZONA, A CORPORATION OF ARIZONA

ENGINE VALVE

Application filed March 29, 1927. Serial No. 179,321.

This invention particularly pertains to an engine valve of the slide valve type for controlling the intake and exhaust of fluid pressure operated engines, such as steam engines, 5 compressed air engines and more especially internal combustion engines.

An object of the invention is to provide an engine slide valve and a mounting therefor so constructed and arranged that pressure developed in the engine cylinder will act to maintain the valve against its seat and whereby leakage of gases from the engine cylinder around the valve is inhibited.

Another object is to provide an engine 15 valve of the above character with means for normally maintaining the valve in a properly seated position during the period when gas pressure in the engine cylinder is not functioning to seat the valve, and which will 20 cooperate at other times with such gas pressure in maintaining the valve seated, and which will also serve as a constant take-up to compensate for wear of the contacting surface of the valve and its seat.

Another object is to provide a connection 25 between the slide valve and its operating mechanism which will permit the valve to accommodate itself to its seat at all times and whereby no forces will be imposed upon the 30 valve from its operating mechanism that would tend to unseat the valve.

Another object is to provide a slide valve 35 which is so constructed and arranged that when applied to an internal combustion engine any pitting or defacing of the surface of the valve or its mounting exposed to the hot gases in the engine cylinder will not interfere with proper functioning or seating of the valve.

Another object is to provide a slide valve 40 for internal combustion engines in which the valve guides are so arranged that wear thereof will not permit ingress of unwanted air on the intake side of the engine and the egress 45 of gases on the exhaust side, and whereby accumulations of carbon will not be a detriment to operation of the valve.

A further object is to provide a slide valve 50 mounting which will afford ready access to the valve without removing the engine head.

With the foregoing objects in view together with such other objects and advantages as may later appear, the invention resides in the features and in the parts, construction, arrangement and combination of parts hereinafter described and claimed and illustrated by way of example in the accompanying drawings in which:

Fig. 1 is a medial vertical section of the slide valve with parts shown in elevation and depicting it as applied to the cylinder of an internal combustion engine and showing a preferred form of valve operating mechanism.

Fig. 2 is a detail in horizontal section as seen on the line 2—2 of Fig. 1.

Fig. 3 is a detail in vertical section and elevation as seen on the line 3—3 of Fig. 1.

Fig. 4 is a view depicting a modified form of the valve operating mechanism shown in Fig. 1.

Fig. 5 is an elevational view illustrating a further modified form of the valve operating mechanism.

Fig. 6 is a sectional view showing the invention as applied to a double slide valve.

Referring to the drawings more specifically 5 indicates the side wall of an engine cylinder which is formed adjacent its upper end with a port 6 constituting either an intake 80 or an exhaust port.

In carrying out my invention the outer face of the wall 5 is formed with a wall surface 7 that is preferably flat and extending over this surface is a valve housing 8 having an inner 85 flat face 9 which is spaced from the surface 7 and which forms a seat for a slide valve 10 mounted for reciprocal movement in the chamber 11 extending between the surfaces 7 and 9. The chamber 11 is bounded by a wall 12 extending between the surfaces 7 and 9 which wall is preferably formed on the engine cylinder wall 5 as shown but which may be formed on the housing 8 or in any other desired manner.

The slide valve 10 is formed of a thickness slightly less than the distance between the wall surfaces 7 and 9 so that when the valve is seated on the surface 9 a clearance will be afforded between the inner face of the valve and the surface 10 as indi- 100

cated at A which clearance is sufficient to permit extreme expansion of the valve and its enclosing walls without bringing the inner face 14 of the valve into frictional contact with the surface 7 thus obviating any possibility of binding of the valve due to such expansion. This arrangement also serves to negative any possibility of the functioning or proper seating of the valve being interfered with by reason of pitting of the valve surface 14 exposed to the interior of the engine cylinder through the port 6. Clearances B and C are provided at the sides of the valve to permit lateral expansion thereof and of the walls 12 without binding of the valve. The chamber 11 extends above and below the port 6 and to each side thereof, and also extends beyond the ends of the valve at the limits of its stroke so as to afford carbon receiving chambers D and E.

The housing 8 is formed with a passage 15, the outer end of which communicates either with an intake or exhaust manifold, not necessary to be here shown, and the inner end of which opens to the chamber 11 through the valve seating surface 9 directly opposite the port 6 in the engine cylinder wall. The valve 10 is formed with a port 16 extending transversely therethrough which port is adapted to form a communication between the port 6 and passage 15 when the valve is disposed in the position shown in dotted lines in Fig. 1, which communication is closed by the valve when the latter is positioned to dispose port 16 out of register with the port 6 and passage 15 as shown in full lines in Fig. 1.

The housing 8 is formed with a slot 17 and connecting with the outer face of the valve is a stem 18 which passes through the slot 17 and connects with a suitable valve operating mechanism indicated generally at F in Figs. 1 and 3 and designated at G and H in Figs. 4 and 5 respectively. The stem 18 is preferably connected to the valve by means of a ball and socket joint I, is here shown as embodying a ball element 21 on the valve which projects into a socket 22 formed on the inner end of the stem 18. To provide the ball and socket connection the stem 17 is here shown as formed of an open ended tube the inner end of which is turned inwardly over the ball 21 and the ball is formed with a threaded shank 23 for screw engagement with the valve and is provided on its outer face with a tool receiving slot 24 adapted to be engaged by a screw driver inserted through the outer end of the tubular stem whereby the threaded shank 23 may be screwed in or out of engagement with the valve. A sleeve 25 is mounted on the stem 18 for longitudinal movement thereon which sleeve is formed with a shoulder 25' arranged to seat on the side margins of the slot 17 to limit inward movement of the sleeve relatively to the stem, and bearing 65 in a recess on the outer end of the sleeve is an

expansile spring 26, the outer end of which bears against a collar 27 having screw engagement with the stem 18 for longitudinal adjustment on the latter to enable adjustment of the tension of the spring. The spring 26 thus exerts an outward thrust on the stem 18 to normally maintain the slide valve in a seated position on the surface 9 of the valve housing, and also serves as a continuous automatic take-up to compensate for wear of the contacting surfaces between the valve and the seat. The ball and socket connection I between the stem and valve serves to prevent any lateral forces imposed on the stem 18 from being transmitted to the valve so as to prevent the valve from becoming unseated by reason of such forces. The valve may be reciprocated in any desired manner to move the port 16 therein in and out of register with port 6 and passage 15; being shown in Fig. 1 as effected by means of a cam 28 on a timing shaft 29 which actuates a stem 30 connecting with the sleeve 25; the stem 30 being fitted with a roller 31 which seats on the cam and being provided with an expansile spring 32 arranged to yieldably oppose movement of the stem and valve under the urge of the cam and operable to move the stem toward the cam. In the construction shown in Fig. 1 the cam moves the valve to its open position. In the form of valve operating mechanism shown in Fig. 4 the roller 31 on the valve stem 30 is engaged in a cam groove 33 on a cam 34 whereby on rotation of the cam the stem and valve will be reciprocated positively in both directions. In this instance the spring 32 will only serve to maintain the roller 31 against the inner wall of the cam groove. In the form of valve operating mechanism shown in Fig. 5 an eccentric 40, 105 on a rotating shaft 41 driven from a timing shaft 42 through gears 43 and 44, engages a strap 45 carried by the sleeve 25 which construction affords positive reciprocal movement of the valve in both directions. In this construction the sleeve 25 is in the form of a slide block having parallel side faces which project into the slot 17 in slidable contact with the parallel side walls of the latter so as to hold the sleeve against turning on the stem 18.

The operation of the invention is apparent from the foregoing, it being seen that on rotation of the timing shaft the slide valve will be reciprocated through the medium of the instrumentalities actuated from the timing shaft. Proper timing of the valve is affected in the usual manner, and cooling of the valve and lubrication thereof may be accomplished in an approved manner.

It will be observed that by arranging the valve seat on the side thereof opposite the port communicating with the engine cylinder pitting of the bearing face of the valve will be practically prevented, and that by

employing the pressure developed in the engine cylinder as an aid in maintaining the valve constantly seated comparatively little leakage if any, will occur around the valve. 5 By forming the inner face 14 of the valve to extend parallel with the surface 7 of the engine cylinder such deposits of carbon as may accumulate in the clearance A will not interfere with functioning of the valve, but 10 on the contrary will serve as a packing, and by providing substantial clearances or chambers D and E at the ends of the valve deposits of carbon may accumulate therein, in event such deposits should occur without impeding 15 movement of the valve for a considerable length of time. In event such deposits should occur excessively the carbon may be readily removed by detaching the housing 8 from the engine cylinder. It is to be noticed that reciprocation of the valve on its seating surface under pressure of the engine gases and the urge of the spring 26 cleaning of this surface will be accomplished.

The invention is applicable to engine valves 25 of the double slide valve type as shown in Fig. 6 in which embodiment a pair of slide valves 46 and 47 are arranged to seat against each other with the innermost valve 46 spaced from the outer surface 7 of the engine cylinder and with the outer valve 47 seating on the housing wall 9'. A stem 18' on the inner valve 46 extends through a slot 48 in the valve 47 which stem together with a stem 50 on the valve 47 extends through a slot on 30 the valve housing and are connected with suitable operating means; the stems being fitted with spring means for normally maintaining the valve 46 against valve 47 and the valve 47 against the seat 9' in the manner before described with reference to the single 35 valve construction.

An important feature of the invention resides in the arrangement whereby the slide valve by reason of extending over the housing slot 17, which serves as a guide-way for the stem and valve, will afford a means for preventing leakage through the valve stem guide to or from the engine cylinder in event of wear of the guide elements; the slide valve 50 being dimensioned to extend over and close the housing slot 17 at all times.

While I have shown and described a specific embodiment of my invention, I do not limit myself to the exact details of construction and arrangement shown, but may employ such modifications, equivalents, and changes in construction and arrangement as come within the meaning and scope of the appended claims.

60 I claim:

1. In an engine valve construction, a valve housing embodying a chamber in open communication with an engine cylinder, a slide valve in said chamber seating on a surface on 65 the side thereof opposite said communication

and the other side of which is exposed throughout to the cylinder through said communication and arranged so that pressures developed in the engine cylinder will be imposed on the valve throughout the inner face thereof and thereby act to press the valve against its seat throughout the travel of said valve, and means for effecting reciprocation of the valve connecting therewith through a slot covered at all times by said valve. 70

2. In combination with an engine cylinder wall having a port, a slide valve operable to cover and uncover said port arranged exteriorly of said cylinder and spaced from said wall, and a valve housing covering said slide valve on which the outer face of said valve seats throughout the travel of said valve. 80

3. In combination with an engine cylinder wall having a port, a slide valve operable to cover and uncover said port arranged exteriorly of said cylinder and spaced from said wall, a valve housing covering said slide valve on which the outer face of said valve seats, and spring means exerting a pull on said valve from the exterior thereof co-operating with gas pressures in the engine cylinder for maintaining the valve against its seat throughout the travel of said valve. 85

4. In combination with an engine cylinder wall having a port, a housing having a flat face spaced from the external face of the cylinder wall around said port forming a valve chamber, a reciprocating slide valve in said chamber seating on said flat face and spaced from the cylinder wall whereby gas pressure in the engine cylinder will press said valve against said face, a stem on said valve projecting through said housing, and a spring exerting an outward thrust on said stem cooperating with the gas pressure in maintaining the valve on its seat throughout the travel of said valve. 100

5. The combination with an engine cylinder embodying a wall having a port, a housing having a flat face spaced from the external face of the cylinder wall around said port forming a valve chamber, a reciprocating slide valve in said chamber seating on said flat face and spaced from the cylinder wall whereby gas pressure in the engine cylinder will press said valve against said face, a stem on said valve projecting through said housing, a spring exerting an outward thrust on said stem cooperating with the gas pressure in maintaining the valve on its seat, and a flexible connection between said stem and valve. 110

6. In combination with an engine cylinder wall having a port, a slide valve operable to cover and uncover said port arranged exteriorly of said cylinder and spaced from said wall, a housing extending over said valve against which the valve slidably seats, a tubular stem extending through a slot in said 125

housing, a ball having screw engagement with said valve extending into and engaged by said tubular stem, and spring means exerting an outward thrust on the stem for maintaining said valve seated against said housing.

5 In testimony whereof, I have affixed my signature.

JOHN H. GRUBE.
